UNITED STATES PATENT OFFICE.

LIDEI E. HIGGINS, OF NEW YORK, N. Y.

BROOM-HOLDER.

No. 894,642.

Specification of Letters Patent.

Patented July 28, 1908.

Application filed December 10, 1907. Serial No. 405,917.

To all whom it may concern:

Be it known that I, LIDEI E. HIGGINS, a citizen of the United States, residing in New York, borough of Manhattan, county and 5 State of New York, have made a new and useful Invention in Broom-Holders, of which the following is a specification.

My invention is directed particularly to a novel means for holding or securing a broom 10 in place against a door, wall, or other means of support, and it has for its objects, first, to provide a holder of this nature which shall be cheap, simple, and efficient. Second, to provide a holder of this nature which may be 15 readily attached to or detached from its permanent means of support and which will retain the head of the broom in perfect shape. Third, to provide a holder of this nature with means for sustaining a dust-pan or dust- 20 cloth, or both.

My invention will be fully understood by referring to the accompanying drawings, in which,

Figure 1 is a front elevational view thereof 25 showing the same attached to a door or other means of support, said holder being partly broken away for the purpose of illustrating the means for hanging it to the door or support, and also showing the broom in place. 30 Fig. 2 is a longitudinal sectional view taken through the body of the holder, illustrating the broom and the door or means of support in side elevational view.

Referring now to the drawings in detail A 35 represents the handle and B the head of an ordinary broom and H represents as a whole my novel form of broom holder or support, the same being preferably made of pressed metal and having the conformation or shape 40 of the broom head B, said holder being open at its back for the reception of the broom and provided at its lower end with an opening I for retaining the handle in position when the holder is closed against a door or 45 rigid means of support D. This holder is formed preferably of pressed metal and is provided around its outer edge with a strengthening bead which incloses a continuous wire W, said wire being bent back 50 and forth upon itself and outward at the upper end so as to constitute a hook E, and around the lower end of the opening I and outward so as to constitute a second hook F, these hooks serving the purpose of support-

ing any article of household use ordinarily 55 utilized in connection with a broom, as, for instance, a dust-pan on one and a dust-cloth upon the other.

G represents a metallic hinge having one edge bent around a portion of the wire W 60 and provided with slotted screw-holes K, K, K for receiving flat-headed screws J, J, adapted to detachably secure the holder to the door or support D. The opposite ends of the wire W approach each other at points 65 approximately opposite the hinge G, and the continuation of the bead therearound constitutes a sliding means of support for a wire catch C which serves also the function of a handle or means of turning the holder H 70 about its hinged point of support G. P represents a locking screw or pin for securing the catch C.

In using this improved holder to secure and protect a broom, the catch C is moved 75 into the upper position indicated in dotted lines, thereby releasing the holder, after which it is rotated about the hinge G a sufficient distance to permit of the insertion of the broom head B with the handle A extending downward through the opening I. The holder and broom are then turned until the outer or beaded edge rests firmly against the door or support D, after which the catch C is moved to its lower or locked position be- 80 hind the pin P.

I am aware that it is not broadly new with me to provide a broom holder which retains the conformation or shape of a broom head and to hang or support such a holder from a 90 fixed point, as a nail or screw, attached to a door or wall, and I make no claim hereinafter broad enough to include such a structural device.

Having thus described my invention what 95 I claim and desire to secure by Letters Patent of the United States is—

1. As an article of manufacture a pressed metal broom holder having the conformation of the head of a broom and provided with a 100 bead extending around its outer rim, said bead inclosing a continuous stiffening wire which is bent outward at the opposite ends of the holder to constitute a means of support for additional articles, substantially as de- 105 scribed.

2. As an article of manufacture a pressed metal broom-holder open at its back and pro-

vided with a strengthening bead extending around its outer edge and inclosing a continuous wire; a hinge secured to said wire on one side and a sliding catch secured within the bead on the other side, substantially as described.

In testimony whereof I have signed my

name to this specification in the presence of two subscribing witnesses.

LIDEI E. HIGGINS.
